DEFLECTING TOOLS

Onos M. Lindsay, Long Beach, Calif., assignor to Eastman Oil Well Survey Company, Long Beach, Calif., a corporation of Delaware

Application November 4, 1954, Serial No. 466,728

12 Claims. (Cl. 255—1.6)

This invention relates to new and useful improvements in deflecting tools.

One object of the invention is to provide an improved deflecting tool for effectively drilling a well bore at an angle from the vertical whereby directional drilling of the well may be accomplished.

An important object of the invention is to provide an improved deflecting tool adapted to be connected in the lower portion of a drill pipe or string and having an expandable-type means for urging the lower portion of the drill pipe and the drill bit attached thereto toward one side of the well bore, whereby subsequent rotation of the drill pipe and bit will result in drilling the well bore at an angle with respect to the remainder of the bore.

Another object is to provide a deflecting tool having an improved deflecting element which is normally in a retracted position and is adapted to be moved radially outwardly by the imposition of the weight of the drill pipe thereon, whereby said element is automatically moved into expanded or extended position when the drill pipe weight is imposed upon the bit to perform the drilling operation.

An important object is to provide an improved deflecting tool having a deflecting element which includes movable actuating members or rods embedded within an elastic body in such manner that when the body is in a normal undeformed position the actuating members are retracted; movement of the members to an extended or radially expanded position functioning to deform said elastic body which thereafter acts, by reason of its inherent property of tending to return to a normal undeformed position, to urge the actuating members toward retracted position.

Another object is to provide an improved deflecting element for a deflecting tool wherein actuating members or rods which are arranged to be operated to expand or radially extend the deflecting element are embedded within an elastic body of material which protects said actuating members against contact with fluid or other material within the well bore; said elastic body also functioning to positively return the actuating members to retracted position upon operation of the tool to effect such retraction.

A particular object is to provide a deflecting tool which is arranged to be mounted in close proximity to or adjacent the drill bit whereby said tool, when expanded, maintains a constant radial pressure or force upon the bit to constantly force said bit laterally of the well bore to thereby accomplish a directional drilling operation.

Still another object is to provide an improved deflecting tool, of the character described, which is simple in construction and which comprises a unitary assembly capable of being readily connected in the usual drill pipe.

A further object is to provide a tool, of the character described, including an improved orienting means whereby the deflecting element of the tool may be located in a desired azimuthal position.

2

Another object is to provide a deflecting tool, of the character described, wherein the main portion of the tool comprises a pair of telescoping members which are so arranged that the relative movement of the members with respect to each other controls the radial extension and retraction of a deflecting element.

The construction designed to carry out the invention will be hereinafter described, together with other features thereof.

10 The invention will be more readily understood from a reading of the following specification and by reference to the accompanying drawings forming a part thereof, wherein an example of the invention is shown, and wherein:

15 Figure 1 is an elevation of the lower portion of a drill pipe within a well bore and showing the improved deflecting tool connected therein,

Figure 2 is a vertical sectional view of a deflecting tool, constructed in accordance with the invention, and 20 illustrating the deflecting element thereof in its retracted position,

Figure 3 is a similar view, with the deflecting element of the tool radially extended or expanded,

Figure 4 is a horizontal, cross-sectional view, taken 25 on the line 4—4 of Figure 2,

Figure 5 is a horizontal, cross-sectional view, taken on the line 5—5 of Figure 2,

Figure 6 is a horizontal, cross-sectional view, taken 30 on the line 6—6 of Figure 2,

Figure 7 is an elevation of the lower portion of the tool, illustrating the deflecting element in full elevation, and

Figure 8 is a partial isometric view, illustrating a portion 35 of the inner telescoping member of the tool,

Figure 8a is an isometric view of the deflecting element and illustrating the orienting lug,

Figure 9 is an isometric view of the deflecting shoe or block, and

Figure 10 is a transverse sectional view, taken on the 40 line 10—10 of Figure 9.

In the drawings, the numeral 10 designates the usual drill pipe or drill stem which is adapted to extend through the well bore W and which is utilized to impart rotation to the drill bit 11 connected to the lower end of said drill pipe (Figure 1). The improved deflecting tool

45 A comprising the present invention is interposed between the drill pipe 10 and drill bit 11 and said tool includes a deflecting element generally indicated at B.

As will be explained in detail, the deflecting element

50 B includes deflecting members or shoes which are capable of movement in a radial direction from a retracted position to an expanded or extended position. The deflecting members are located on one side of the element B, whereby when said members are extended radially, as

55 shown in Figures 1 and 3, said members contact the wall of the well bore W at one side thereof just above and in close proximity to the drill bit 11; this contact of the deflecting members or shoes with one side of the well bore results in the application of a lateral force against

60 the drill bit in a direction 180 degrees opposite the point of contact and thus, with the deflecting members or shoes in a radially extended position during a drilling operation, the bit is constantly urged in a lateral direction to drill the well bore at an angle with respect to

65 the axis of the bore in which the tool is located. By proper orientation of the deflecting members or shoes of the element B a directional drilling operation may be carried out.

The deflecting tool A is clearly shown in Figures 2 70 to 10 and includes a pair of telescoping sections T and T1. The upper section T comprises a tubular sub or

body 12 which is adapted to have its upper end connected with the drill pipe 10. A sleeve 13 which is threaded onto the lower portion of the sub 12 depends therefrom and has internal longitudinally extending drive splines or keys 14 provided within its bore. The sub is formed with an axial bore 12a extending entirely therethrough and the upper end of the bore is in communication with the bore 10a of the drill pipe whereby circulation of the usual drilling fluid may be directed to the bit. The lower end of the sub is reduced as indicated at 12b and a fluid conductor tube 15 which is threaded into the lower end of the bore 12a depends from said sub. A ring or washer 12c, is threaded onto the tube in abutting relationship to the sub and actually forms the lower end of the sub.

The lower telescoping section T1 comprises a main body 16, having an axial bore 17 and said body is slideable axially within the bore of the sleeve 13 of the upper section. An external flange 18 is formed on upper end of the body 16 and below this flange a plurality of longitudinal drive splines or keys 19 are provided (Figure 8); the splines 19 interengage and fit with the longitudinal splines 14 within the sleeve 13 of the upper section T and the engagement of the keys 19 and 14 rotatively couple the body 16 to the sleeve, while permitting relative sliding movement between the parts in an axial direction. Movement of the sleeve upwardly with respect to the body is limited by the engagement of the upper ends 14a of keys 14 with the annular flange 18 of the body 16.

The fluid conductor tube 15 which has its upper end threaded into the lower end of the bore 12a of sub 12 extends downwardly in telescoping relationship into the bore 17 of the body 16; suitable packing 20 seals off between the bore 17 and the exterior of the tube and said tube provides a flow conductor for conducting fluid downwardly from the bore 10a of the drill pipe and bore 12a of the sub to the bore 17 of the body 16 in all positions of the telescoping sections T and T1 with respect to each other. A coil spring 21 is interposed between the upper end of the body 16 and a shoulder 12d on the lower portion of the sub 12 and exerts its pressure to normally urge these parts away from each other, whereby the sections T and T1 are constantly urged toward an extended position.

A tubular coupling or mandrel 22 is threaded onto the lower end of the body 16 of the lower section T1 and is provided with an axial bore 22a which forms a continuation of bore 17. The drill bit 11 is connected to the coupling or mandrel 22 and obviously circulation of drilling fluid to the bit may be accomplished through the bores of the various parts of the tool sections.

The coupling 22 has an annular enlargement at its lower end whereby an annular supporting shoulder 23 is formed thereon. A bearing ring 24 rests upon the shoulder and said ring and shoulder support the deflecting element B which has deflecting members which are arranged to be expanded or radially extended to properly deflect the drill bit 11 in a desired manner.

The deflecting element B comprises a tubular sleeve or support 25 which surrounds the coupling or mandrel 22 and which is rotatably supported upon the annular shoulder 23, said sleeve engaging the bearing ring 24. A body 26 of elastic or resilient material is molded to one side of the sleeve 25 (Figure 4) and is generally arcuate in cross-section with its longitudinal edges 25a merging into the exterior surface of the sleeve at points approximately 180 degrees opposite each other. The elastic body is preferably formed with a trio of ribs 26a, 27 and 28 which are spaced approximately equidistant around the body and each rib has associated therewith a metallic deflecting shoe or block 29. Although three longitudinal ribs are illustrated, the invention is not to be limited to this number and actually, the invention would be operable with only the single central rib 27. As is clearly shown in Figures 9 and 10, each shoe or

block includes an elongate body 30 having outwardly directed side flanges 31. The block is formed with slots or recesses 32 and 33 which extend from the ends of the block to the central portion thereof. Within the central portion of the block, an inclined opening 32a forms a continuation of the recess 32 while a second inclined opening 33a forms a continuation of the recess 33. The openings 32a and 33a may be in communication with each other (Figure 2).

Each deflecting shoe or block 29 is embedded, as by molding, within the elastic or resilient body portion 26 and is disposed at substantially mid-height of said portion. For actuating said shoe or block a pair of actuating members or rods 34 and 35 are provided and these rods are also embedded or molded within the elastic body portion. The upper rod 34 has its lower end extending through the recess 32 in the shoe and is engaged within the opening 32a, while the upper end of the lower rod 35 is confined within the slot 33 and is engaged within the opening 33a. When the elastic or resilient body 26 is in a normal undistorted position, each pair of rods is in the position shown in Figure 2, whereby the deflecting shoe or block associated with the rods is in a retracted position; at such time the upper end of each upper rod 34 projects in a plane above the elastic body 26 and the lower end of each lower rod extends below the lower end of said body and the rods are disposed at an incline relative to the axis of the sleeve. This inclination of the rods locates the abutting ends of each pair of rods further outwardly in a radial direction than their respective outer ends, whereby an endwise pressure on said rods will cause the abutting portions thereof, which are connected to the associated deflecting shoe, to move further outwardly in a radial direction. In other words the normal disposition of each pair of rods is such that upon an endwise pressure being applied, said rods act much in the manner of a toggle linkage to move the deflecting shoe radially outwardly to an extended position. A bearing ring 36 of suitable bearing material is secured to the lower end of the sleeve 13 and is adapted to engage a ring 36a which engages the upper ends of the upper rods 34 when the sections T and T1 are telescoped with respect to each other.

When the sections T and T1 are moved to a telescoped position, the sleeve 13 applies pressure to the upper ends of each pair of actuating rods 34 and 35 through the rings 36 and 36a and said rods are, in fact, confined between the sleeve 13 of the upper section and the supporting shoulder 23 of the lower section; the endwise pressure so applied results in the abutting ends of each pair of rods moving radially outwardly to accomplish a radial extension of each deflecting shoe 29 (Figure 3). This movement of the rods and deflecting shoes is permitted because the elastic or resilient material of the body 26 which, in effect, supports these parts, deforms sufficiently to allow such movement. The inherent elasticity of the elastic body 26 tends to constantly urge the rods and deflecting shoes toward their retracted position, but so long as the sections T and T1 are telescoped and pressure maintained on said rods, the deflecting shoes are held in their extended position. Each shoe is provided with hardfacing material 37 on its external surface and when said shoes are moved to a radially extended position, the hardfacing material thereof engages the wall of the well bore. Since all of the deflecting shoes are on one side of the sleeve, it is evident that their radial extension results in applying a lateral pressure to the drill bit which pressure is in a direction substantially 180 degrees opposite the deflecting shoe mounted in the central rib 27 of the body portion 26 of the deflecting element.

When the telescoping sections are extended (Figure 2), the inherent elastic or resilient action of the material of the body portion returns the body 26 to its normal undeformed position which will result in returning the rods 34

and 35 to their normal position, whereby a retraction of the deflecting shoes 29 is effected. The coiled spring 21, of course, assists in moving the telescoping sections T and T1 to their extended position. It is noted that the elastic body 26 not only acts in the manner of a spring means to retract the deflecting shoes but since the shoes, as well as the actuating rods are molded or otherwise embedded therein, said body 26 protects these parts against contact with fluids and other foreign matter within the well bore.

To provide means for orienting the deflecting element, the sleeve 25 on which the deflecting element is mounted is provided with an enlargement 22b within which an arcuate recess 38 is formed. An arcuate orienting lug or member 39 is slidable within said recess and coil springs 40 constantly urge the lug in an upward direction. The orienting lug 39 (Figure 8) is adapted to engage a recess 41 which is formed in the exterior of the body 16 of the lower telescoping section T1. As shown in Figure 8, the recess 41 is formed by removing portions of certain of the splines 19 on the body and when the lug 39 is engaged within the recess, the sleeve 25 of the deflecting element B is non-rotatable with respect to the body 16 of the lower telescoping section T1. When the members are fully telescoped to effect a radial extension of the deflecting shoes as shown in Figure 3, the lower end of sleeve 13 of the upper section T has engaged the orienting lug 39 and has moved the same downwardly, thereby disengaging said lug from its recess 41. At such time the telescoping sections T and T1 may be rotated with respect to the deflecting element so that a drilling operation may be carried out. During such drilling the deflecting element B remains stationary so far as rotation is concerned and the radially extended deflecting shoes 29 merely slide downwardly on the wall of the well bore as drilling progresses.

In the operation of the device the parts are normally in the position shown in Figure 2 with the sections T and T1 in an extended position. In such position, the deflecting shoes of the element B are in a normal retracted position and the orienting lug 39 is engaged with its recess 41 to latch the deflecting shoes in a fixed radial position relative to the section T1. The drill pipe is, of course, connected to the upper section T which is coupled to the lower telescoping section T1 through the drive splines 14 and 19.

By locating a magnet 50 (Figure 1) in the drill pipe in a known radial position or relationship to the shoes 29 of the deflecting element B, it is possible to determine the radial position or azimuth of the deflecting shoes by known methods of bottomhole orientation. For example, a method of orientation which may be employed is that shown in the patent to Miller 2,327,658 or Hyer 2,120,670. With the magnet 50 in a known radial relationship to the deflecting shoes of the element B when the same is in latched position with respect to the drill pipe, a suitable surveying instrument illustrated in dotted lines in Figure 1 may be lowered through the bore, then operated and its record subsequently examined so that the compass position of the deflecting shoes may be readily determined after the tool has been lowered into position and just prior to the commencement of the drilling operation.

Upon reaching bottom, the drill bit 11 strikes the bottom of the well bore and thereafter the weight of the drill pipe is imposed upon the tool. This causes a telescoping of the upper section T with respect to the lower section T1 and such movement applies an endwise force to the extended ends of the actuating rods 34 and 35, whereby the deflecting shoes 29 move to the radially extended position shown in Figure 3. At the same time the orienting lug 39 is disengaged from its recess 41 to render the sections T and T1 rotatable with respect to the deflecting element.

When the deflecting shoes of the element B are moved

radially outwardly, said shoes contact the wall of the bore and apply a radial or lateral pressure to the drill bit to urge the bit in a direction which is opposite the position of the deflecting shoes and thus the bit is urged to one side of the bore. By properly orienting the deflecting element, the bit is urged laterally in a desired compass direction, and thereafter it is only necessary to impart rotation to the drill pipe to effect a direct drive from the upper telescoping section T, through the drive splines 10 to the lower section T1 and to the drill bit, whereby a drilling operation may be performed. It is evident that so long as the weight of the pipe is imposed upon the tool, the sections T and T1 remain in telescoped position and maintain the shoes of the deflecting element B in their expanded position. Since the orienting lug 39 is disengaged from its recess 41 when the parts are fully telescoped, the deflecting element B may remain stationary while the remaining parts of the tool may rotate with the bit. Therefore, as the drilling operation proceeds, the deflecting shoes of the deflecting element merely slide down the wall of the well bore, but at the same time maintain a constant lateral pressure on the drill bit to constantly urge it toward the opposite wall of the bore being drilled. It is pointed out that the deflecting element B is located 15 in close proximity or adjacent to the drill bit so that the required constant lateral pressure may be maintained throughout the drilling operation.

The tool is extremely simple in construction and comprises a minimum number of parts. It is manipulated 20 solely by the application or removal of weight by means of the drill pipe and with the particular orienting lug arrangement, may be re-oriented without the necessity of the removal from the well bore. The inherent elasticity of the resilient or deformable material of the body portion 25 is utilized to assure the retraction of the deflecting shoes and also said material provides a simple method of mounting the actuating rods and deflecting shoes; at the same time the elastic material effectively protects the various parts from direct contact with the fluids or other 30 matter within the well bore. The actuating members or rods which are embedded within the deformable material assure proper control of the movement of the deflecting element, since said members are disposed so that upon endwise compressive force applied to said members, 35 radial extension of the deflecting shoes is assured.

The foregoing disclosure and description of the invention is illustrative and explanatory thereof and various changes in the size, shape and materials, as well as in the details of the illustrated construction may be made, 40 within the scope of the appended claims, without departing from the spirit of the invention.

What I claim is:

1. A deflecting tool including, an upper telescoping section, a lower telescoping section, said sections being 45 movable relative to each other from a first position in which the sections are extended to a second position in which the sections are retracted, means for rotatively connecting the sections in all positions of said sections, a deflecting element supported upon the lower section and 50 comprising a tubular sleeve having a body of elastic material attached to one side thereof, a deflecting shoe molded to the central portion of the elastic body, a pair of actuating rods embedded within the elastic material and having their inner ends connected with the deflecting shoe and their outer ends projecting beyond the upper and lower ends of the elastic body, and means carried by said upper and lower telescoping sections for engaging the outer ends of said rods as the sections are moved to retracted position, whereby when the sections are moved 55 to said second position an endwise compressive force is applied to the rods to effect a swinging outward movement of the inner ends of said rods to move the deflecting shoe radially outwardly.

2. A deflecting tool as set forth in claim 1, wherein 60 the actuating rods are slightly inclined with respect to

the longitudinal axis of the sleeve with their inner ends a greater distance outwardly in a radial direction than their outer ends when the elastic body is in a normal undistorted position.

3. As a sub-combination in a deflecting tool, a deflecting element for mounting between telescopic elements comprising, an annular supporting sleeve, a body of elastic deformable material which is arcuate in cross-section secured to one side of said sleeve, a deflecting shoe molded within the body at substantially mid-height thereof, and a pair of actuating rods molded within the resilient body, the inner end of one rod being pivotally connected to the shoe with its outer end projecting beyond one end of the body, and the second rod having its inner end pivotally connected with the shoe with its outer end projecting beyond the opposite end of the body.

4. The sub-combination set forth in claim 3, wherein the rods are disposed at an inclination with respect to the longitudinal axis of the deflecting element, with the inner ends of the rods being located at a greater outward radial position than the outer ends thereof when the elastic body is in a normal undeformed position.

5. The sub-combination set forth in claim 3, wherein the outer surface of the body of resilient material is formed with longitudinal ribs, said deflecting shoe being mounted in one of said longitudinal ribs.

6. A deflecting tool including, an upper section, a lower section telescoping said upper section, said sections being movable axially with respect to each other to a first position in which the sections are extended and to a second position in which the sections are more fully telescoped, a deflecting element mounted on one of the sections and including a body of elongate deformable material disposed on one side thereof, said body being in a normal undeformed state when the sections are in said first position relative to each other, and means embedded in said body and engageable by the sections when said sections are moved to said second position for deforming said body radially outwardly to engage its outer surface with the wall of the bore in which said tool is disposed.

7. A deflecting tool as set forth in claim 6, wherein the deflecting element surrounds one of said sections and is rotatably supported with respect to the telescoping sections when in at least one of said positions, whereby said sections may be rotated relative to the deflecting element.

8. A deflecting tool as set forth in claim 6, wherein the deflecting element is rotatably supported with respect to the telescoping sections when said sections are in said second position, and means for locking said element

against rotation relative to the sections when said sections are in said first position.

9. A deflecting tool as set forth in claim 6, together with spring means for constantly urging the telescoping sections toward said first position, and means for setting up a rotative driving connection between said sections in all positions of the sections.

10. A deflecting tool including an upper section, a lower section having a telescoping connection with the upper section, said sections being movable axially with respect to each other to a first position in which the sections are extended and to a second position in which the sections are more fully telescoped, spring means normally urging the sections toward said first position, means for setting up a rotative driving connection between the sections in all positions of the sections, a deflecting element supported upon the lower section and including an elongate deformable body portion on one side thereof, a deflecting member embedded in the surface of the body portion, said deflecting element being in a normal undeformed position when the sections are in said first position relative to each other, and means co-acting with said deformable body and engageable by said sections when said sections are moved to said second position for deforming the body portion radially outwardly to move said deflecting member radially outwardly into engagement with the wall of the well bore in which the tool is disposed.

11. A deflecting tool as set forth in claim 10, wherein the deflecting element surrounds one of said sections and is rotatably supported upon the lower section when said sections are in said second position, and means for locking said element against rotation with respect to both sections when said members are in said first position.

12. A deflecting tool as set forth in claim 10, wherein the upper section is connected to a drill pipe and the lower section is connected to a drill bit, whereby the sections may be telescoped into said second position by the weight of the drill pipe when the drill bit engages the bottom of a well bore.
